DESIGN FOR A SPECTACLE FRAME

Alfred C. Houser, Highland Park, Ill., assignor to
Rosenow Company, Chicago, Ill., a corporation
of Illinois

Application November 28, 1934, Serial No. 54,190

Term of patent 7 years

To all whom it may concern:

Be it known that I, Alfred C. Houser, a citizen of the United States, residing at Highland Park, in the county of Lake and State of Illinois, have invented a new, original, and ornamental Design for Spectacle Frame, of which the following is a specification, reference being had to the accompanying drawing, forming part thereof.

In the said drawing—

Figure 1 is a front view of a spectacle frame

showing my new design, with the temples unfolded, the frame being formed of a single piece of flat material.

Figure 2 is a perspective view of the spectacle frame bent into shape for wearing.

I claim:

The ornamental design for a spectacle frame, as shown and described.

ALFRED C. HOUSER.
